Primary Examiner — Richard Edgar*Assistant Examiner* — Jessica Ruth Grable(74) *Attorney, Agent, or Firm* — Gottlieb, Rackman & Resiman, PC(57) **CLAIM**

The ornamental design for a divider insert for a shelving unit, as shown and described.

DESCRIPTION

FIG. 1 is a perspective view of a first embodiment of a divider insert for a shelving unit illustrating our new design; FIG. 2 is front elevation view of FIG. 1; FIG. 3 is a rear elevation view of FIG. 1; FIG. 4 is a right side elevation view of FIG. 1; FIG. 5 is a left side elevation view of FIG. 1; FIG. 6 is a top plan view of FIG. 1; FIG. 7 is a bottom plan view of FIG. 1; FIG. 8 is a perspective view of a second embodiment of a divider insert for a shelving unit illustrating our new design; FIG. 9 is front elevation view of FIG. 8; FIG. 10 is a rear elevation view of FIG. 8; FIG. 11 is a left elevation view of FIG. 8; FIG. 12 is a right elevation view of FIG. 8; FIG. 13 is a top plan view of FIG. 8; FIG. 14 is a bottom plan view of FIG. 8; and, FIG. 15 is a cross-sectional view of the divider insert for a shelving unit of FIG. 13, taken along line 15-15.

The broken lines in the figures are for the purpose of illustrating environmental structure of the divider for a shelving unit and form no part of the claimed design. The shade lines represent surface shading and not surface ornamentation, color, or material type. The dotted lines with arrows indicate where a cross-sectional view has been taken and form no part of the claimed design.
